US0D1103038S

(12) **United States Design Patent** (10) **Patent No.:** **US D1,103,038 S**
(45) **Date of Patent:** **** Nov. 25, 2025**

(54) **VEHICLE**

(71) Applicant: **United States Postal Service**,
Washington, DC (US)

(72) Inventors: **Daniel Nett**, Oshkosh, WI (US); **Jesse Gander**, Oshkosh, WI (US); **Thomas Quigley**, Oshkosh, WI (US); **David C. McGraw**, Oshkosh, WI (US); **Benjamin Andrews**, Oshkosh, WI (US); **Robert W. Holliday**, Oshkosh, WI (US); **Andrew Drach**, Oshkosh, WI (US)

(73) Assignee: **United States Postal Service**,
Washington, DC (US)

(**) Term: **15 Years**

(21) Appl. No.: **29/911,380**

(22) Filed: **Sep. 1, 2023**

Related U.S. Application Data

(62) Division of application No. 29/770,991, filed on Feb. 18, 2021, now Pat. No. Des. 997,785.

(57) **CLAIM**

The ornamental design for a vehicle, as shown and described.

DESCRIPTION

FIG. 1 is a front, left isometric view of a vehicle in accordance with the new design;

FIG. 2 is a rear right perspective view thereof;

FIG. 3 is a front view thereof;

FIG. 4 is a rear view thereof;

FIG. 5 is a left side view;

FIG. 6 is a right side view thereof;

FIG. 7 is a top view thereof; and,

FIG. 8 is a bottom view thereof.

Broken lines are used to illustrate environmental structure and form no part of the claimed design.

1 Claim, 7 Drawing Sheets
